UNITED STATES PATENT OFFICE

MATHIAS PIER, OF HEIDELBERG, AND RUDOLF WETZEL AND BRUNO ENGEL, OF LUDWIGSHAFEN-ON-THE-RHINE, GERMANY, ASSIGNEES TO I. G. FARBNENINDUSTRIE AKTIENGESELLSCHAFT, OF FRANKFORT-ON-THE-MAIN, GERMANY, A CORPORATION OF GERMANY

SEPARATION OF OILS FROM MIXTURES WITH SOLID SUBSTANCES

No Drawing. Application filed August 17, 1928, Serial No. 300,383, and in Germany October 25, 1927.

This invention relates to improvements in the separation of oils from mixtures thereof with solid substances.

In many technical processes, namely in the low temperature carbonization, cracking and extraction of carbonaceous materials, and also in the destructive hydrogenation of varieties of coal, tars, mineral oils and the like, and similar processes hereinafter referred to for the sake of brevity by the term "heat treatment of carbonaceous materials", there are obtained, inter alia, larger or smaller amounts of products consisting of mixtures of oils of a more or less heavy nature with solid substances containing carbon, such for example as charred residues, ash constituents or other solid impurities, such as catalysts. In such cases it is often difficult to separate the solid constituents from the oil.

We have now found that the separation of the said solid constituents from the oils is greatly facilitated by centrifuging the mixture with an addition of liquids possessing good solvent properties as regards the oil. Such liquids comprise, more particularly aromatic hydrocarbons such as benzene, toluene and xylene, or hydroaromatic substances such as tetrahydronaphthalene, or substances containing chlorine, such as chloroform, methyl-ene chlorid, or also mixtures rich in the same such as brown coal tar oils or coal tar oils, or also fractions of destructive hydrogenation products of the same. If, for example, a product obtained by the destructive hydrogenation of certain brown coals be centrifuged by itself, no separation is obtained at all in many instances. On the other hand if about 30 per cent of one of the above-mentioned substances be added, separation is easily effected with ordinary centrifuges, sometimes even in the cold. In comparison with the usual extraction, this method of working has the special advantage of requiring a far smaller amount of solvent. The solvent which, under certain conditions, may still remain adhering to the residue, can be recovered by warming or by treatment with steam. In order to free the residue extensively from oil, it is often convenient to centrifuge it repeatedly, with the addition of solvents in

which case different solvents may also be employed.

Under certain conditions the procedure may consist in first eliminating a portion of the adherent oil from the mixture under treatment by centrifuging without the addition of a solvent, the oil being displaced, in this case, from the centrifuge by washing with water, after which the centrifuging of the still highly oleaginous residue is resumed after the addition of benzene or the like. In such cases it is advisable to so arrange the centrifuge that the added solvent is able to penetrate well into the residue. According to this manner of working a residue almost entirely free from oil is obtained. In the above case the solid substance from which the oil is to be extracted are free from water or contain only so little water that no aqueous suspensions or pastes of the said solid materials are formed.

It is also advisable, under certain circumstances, to add wetting agents, such as nucleo-alkylated sulfonic acids of aromatic hydrocarbons, cellulose pitch, saturated and unsaturated fatty acids or salts of the same, and the like, which lessen the adhesion between the solid substances and the adherent oils. In some cases, depending on the nature of the oils, it may also be advantageous to work in an alkaline medium, for example with an addition of alkali or of a sulfid of a strongly alkaline metal. When working in the presence of alkaline agents or wetting agents, it may in some cases be advantageous to add water or to employ moist initial materials which may even be present in the form of aqueous pastes or suspensions.

The following examples will further illustrate the nature of the said invention which however is not limited thereto.

Example 1

If a definite quantity of the sludge resulting from the destructive hydrogenation of brown coal be centrifuged at 100° C. without any addition, although an oil practically free from coal is obtained, the centrifuged residue will nevertheless still contain about 40 per cent of oil. On the other hand, if the

sludge be stirred up with 0.5 to 0.6 of its own weight of benzene, and the mixture be centrifuged, a pure oil is also obtained after cooling, whilst the residue will contain, apart 5 from the adherent solvent benzene, only 6 parts of oil which is soluble in benzene. The benzene can be readily recovered from the oil by warming or treatment with steam, and the same applies to the proportion, only 3 to 10 5 per cent, left in the centrifuged residue. Similar results are obtainable by the addition of methylene chlorid, toluene, xylene and the like.

Example 2

15 The residue obtained in the destructive hydrogenation of brown coal is stirred up with 30 per cent of a brown coal tar fraction boiling at from 250° to 300° C., together with the same amount of water, to which a little sodium isopropylnaphthalene-sulfonate has 20 been added. On centrifuging the mixture at 100° C. separation is easily effected into three layers, namely, residue, water and oil.

Example 3

30 The sludge obtained in the destructive hydrogenation of brown coal is centrifuged at 130° C. without any addition. In this way, a portion of the oil contained in the sludge 35 is recovered and is run off, a residue containing from 40 to 45 per cent of matter soluble in benzene being left in the centrifuge. To this is added about one third to half its own weight of heavy benzene also resulting from the destructive hydrogenation process, and centrifuging is continued. In this way the major portion of the oil still contained in the residue is expelled.

Example 4

40 The sludge obtained in the destructive hydrogenation of brown coal is stirred up with half its weight of heavy benzene, with an addition of 0.25 per cent of olein and 0.25 45 per cent of ammonia, the mixture being centrifuged at from 90° to 95° C. and rinsed with a little heavy benzene. A practically pure oil is obtained, together with a residue containing 18 per cent of matter soluble in 50 benzene and consisting chiefly of the added heavy benzene. This can be practically all eliminated from the residue by washing with a hot 0.25 per cent aqueous solution of olein, or Turkey red oil and ammonia until the 55 washing liquid runs away clear and free from benzene. The residue then contains only 1.4 per cent of substances soluble in benzene. The oil is recovered from the washing liquid by neutralization or slight acidification, and 60 is drawn off. If the separated washing liquid be again treated with the corresponding amount of ammonia, it can be used again for washing, with equal efficiency.

What we claim is:—

65 1. A process for the recovery of oils from

mixtures thereof with solid substances containing free carbon, obtained by heat treatment of carbonaceous materials, which comprises centrifuging the said mixtures with an addition of liquid aromatic hydrocarbons 70 possessing good solvent properties as regards the oil.

2. A process for the recovery of oils from mixtures thereof with solid substances containing free carbon, obtained by destructive 75 hydrogenation of carbonaceous materials, which comprises centrifuging the said mixtures with an addition of a liquid possessing good solvent properties as regards the oil.

3. A process for the recovery of oils from 80 mixtures thereof with solid substances containing free carbon, obtained by destructive hydrogenation of carbonaceous materials, which comprises centrifuging the said mixtures with an addition of an organic liquid 85 possessing good solvent properties as regards the oil.

4. A process for the recovery of oils from mixtures thereof with solid substances containing free carbon, obtained by destructive 90 hydrogenation of carbonaceous materials, which comprises centrifuging the said mixtures with an addition of liquid aromatic hydrocarbons possessing good solvent properties as regards the oil. 95

5. A process for the recovery of oils from mixtures thereof with solid substances containing free carbon, obtained by heat treatment of carbonaceous materials, which comprises centrifuging the said mixtures with 100 an addition of a liquid possessing good solvent properties as regards the oil with an addition of an organic wetting agent.

6. A process for the recovery of oils from mixtures thereof with solid substances containing free carbon, obtained by heat treatment of carbonaceous materials, which comprises centrifuging the said mixtures with an addition of a liquid possessing good solvent properties as regards the oil with an addition of a salt of an aromatic sulfonic acid. 110

7. A process for the recovery of oils from mixtures thereof with solid substances containing free carbon, obtained by heat treatment of carbonaceous materials, which comprises centrifuging the said mixtures with an addition of a liquid possessing good solvent properties as regards the oil with an addition of an organic wetting agent and an alkaline agent. 115

8. A process for the recovery of oils from mixtures thereof with solid substances containing free carbon, obtained by heat treatment of carbonaceous materials, which comprises centrifuging the said mixtures with 125 an addition of a liquid possessing good solvent properties as regards the oil with an addition of sodium isopropyl naphthalene sulfonate.

9. A process for the recovery of oils from 130

mixtures thereof with solid substances containing free carbon, obtained by destructive hydrogenation of brown coal which comprises centrifuging the said mixture with an addition of benzene.

10. A process for the recovery of oils from mixtures thereof with solid substances containing free carbon, obtained by destructive hydrogenation of brown coal which comprises centrifuging the said mixture with an addition of about its own weight of benzene.

11. A process for the recovery of oils from mixtures thereof with solid substances containing free carbon, obtained by destructive hydrogenation of brown coal which comprises centrifuging the said mixture with an addition of benzene and sodium isopropyl naphthalene sulfonate.

12. A process for the recovery of oils from mixtures thereof with solid substances containing free carbon, obtained in the destructive hydrogenation of carbonaceous materials which comprises centrifuging the said mixtures with an addition of a liquid possessing good solvent properties as regards the oil with an addition of an organic wetting agent.

13. A process for the recovery of oils from mixtures thereof with solid substances containing free carbon, obtained in the destructive hydrogenation of carbonaceous materials which comprises centrifuging the said mixtures with an addition of a liquid possessing good solvent properties as regards the oil with an addition of a salt of an aromatic sulphonic acid.

14. A process for the recovery of oils from mixtures thereof with solid substances containing free carbon obtained in the destructive hydrogenation of carbonaceous materials which comprises centrifuging the said mixtures with an addition of a liquid possessing good solvent properties as regards the oil with an addition of sodium isopropyl naphthalene sulphonate.

45 In testimony whereof we have hereunto set our hands.
